J. M. BROWNING

AUTOMATIC FIREARM

Filed Sept. 21, 1923

UNITED STATES PATENT OFFICE.

JOHN M. BROWNING, OF OGDEN, UTAH.

AUTOMATIC FIREARM.

Application filed September 21, 1923. Serial No. 664,068.

To all whom it may concern:

Be it known that I, JOHN M. BROWNING, a citizen of the United States, residing in Ogden, in the county of Weber and State of Utah, have invented certain new and useful Improvements in Automatic Firearms, of which the following is a specification, reference being had to the accompanying drawings, forming a part hereof.

10 The invention is for improvements in machine guns and the like in which all operations of the mechanism, except that of the trigger, are automatically effected, and has for its object to provide means for regulating or retarding the rate of firing, while retaining the automatic action.

It has been found that in automatic machine guns, and particularly in automatic machine rifles, as heretofore constructed, the 20 rate of firing may be so rapid when the gun or rifle is being operated with its full automatic action, that is, when the trigger is being held back, as to be a positive disadvantage. The rate of firing may be so rapid 25 that the shooter can not properly aim his gun or rifle, ammunition is wasted and the rapid succession of recoils is so severe, particularly in the case of a machine rifle being shot from the hip or shoulder, that the accuracy of the shooter is much decreased. 30 Also, particularly in the case of the automatic rifle, the gun heats up too rapidly and the rifling in the barrel wears out quickly. It has therefore been found advisable 35 to retard the rate of firing by insuring that there should be a lapse of time between successive shots greater than the time required for the usual recoil and return to battery of the recoiling parts.

40 To that end I provide novel means which retard or slow down the rate of firing by preventing the return of the firing mechanism to battery after recoil until after the lapse of a desired period of time. According 45 to my present invention, on the firing of a shot the retarding mechanism is moved into operative position to insure that the firing mechanism shall be cocked on the recoil thereof and to positively prevent the 50 firing mechanism from being released to fire the next shot until the retarding mechanism has moved from operative to inoperative position, and the time taken for this movement of the retarding mechanism from

operative to inoperative position can be 55 regulated to insure the desired lapse of time between shots.

I illustrate my invention as applied to the automatic machine rifle such as is shown and described in my United States Patent 60 No. 1,293,022, and the accompanying drawings show those parts of the machine rifle of said patent to which my new invention is applied.

In the accompanying drawings, Fig. 1 65 represents a longitudinal vertical section of the central portion of the machine rifle with the parts in firing position and certain parts in elevation.

Fig. 2 represents a plan view of the trigger 70 casing and its accompanying parts.

Fig. 3 represents a vertical longitudinal section of the retarding mechanism with the sear and action-slide in cocked position after recoil. 75

Fig. 4 represents a longitudinal vertical section of a portion of the action-slide, a portion of the trigger-guard, and the trigger and sear in cocked position.

Fig. 5 represents a left hand side view of 80 the retarding lever latch and of the right hand rear portion of the retarding lever, with a portion of the retarding lever in section.

Fig. 6 represents a front view of the escapement ratchet and pawl. 85

Fig. 7 represents a vertical transverse section in the line 7—7 of Fig. 1.

The following main parts of the machine rifle shown and described in the Patent No. 90 1,203,022 are shown in the drawings:

The hammer 1; the action-slide 2; piston-rod 3; piston 4; reaction spring 5; buffer plate 6; breech casing 7; butt stock 8; magazine release 9; magazine catch 10; magazine 95 11; trigger 12; trigger-plate or guard 13; and sear 14.

The trigger is pivoted at its forward end on pivot-pin 12^a, which extends transversely through the trigger-guard. In Figs. 1, 3 100 and 4 the trigger is shown in its normal inoperative position, to which it is returned by the sear spring after being pulled back to unlock the firing mechanism as herein-after described. Rearward projection 12^b 105 engaging the trigger-guard prevents the trigger from swinging down beyond the position shown in Figs. 1, 3 and 4.

The sear 14 is pivoted on pin 14^a seated in the ears 13^a projecting upwardly from the trigger guard on each side. The pin 14^a passes through a longitudinal slot 14^b in the sear, whereby the sear can not only rotate on its pivot but can have a limited longitudinal movement for purposes herein-after described. A sear spring 14^c is seated in a recess in the under side of the sear and 10 engages at its forward end the fixed pin 15 which projects transversely through the trigger-guard under the pin 14^a. As shown in Fig. 1, said spring normally holds the sear in its rearward position with its rear 15 arm in raised position and the pivot pin 14^a in engagement with the front face of the slot 14^b, whereby the end of the rear arm of the sear will engage the cocking shoulder 2^a on the bottom face of the action-slide when the action-slide moves forward 20 after its recoil, and hold the action-slide and hammer cocked until the front arm of the sear is raised by the trigger as herein-after described. In Figs. 1, 3 and 4 the trigger is 25 in its normal, inoperative position, and if the retarding lever 19 is in its inoperative position, as herein-after described, a rearward pull on the trigger will bring the top of the upwardly projecting arm 12^c of the trigger into engagement with the end of the forward arm of the sear, rock the sear on 30 its pivot and free the action-slide and hammer for forward firing movement under the action of the spring 5.

35 Pivoted on pin 17, which projects transversely through the trigger guard, is the combined ratchet 17^b and escapement wheel 17^c (Fig. 6). An escapement pawl 18 is pivoted on pin 18^a, which projects transversely through the trigger guard below 40 pivot pin 17. Said escapement pawl is positioned for engagement with the teeth of the escapement wheel 17^c.

45 19 is a retarding and trigger-locking lever pivoted at its rear end and centrally of the trigger guard on pin 19^a which projects transversely through the trigger guard. Pivoted on the forward end of the retarding lever and projecting downwardly therefrom is the ratchet pawl 20 having teeth 20^a to engage the teeth of the ratchet 17^b. Seated in the head of the retarding and trigger-locking lever is the ratchet pawl spring 20^b having its upper end 50 seated against a rearward projection on the ratchet pawl and thereby pressing the lower end of the pawl rearwardly and holding the teeth of said pawl in engagement with the ratchet 17^b. It will be noted (see Fig. 2) 55 that the retarding lever is not parallel with the sides of the trigger-guard throughout its length, but for a portion of its length is inclined to the left, whereby its front end is in a vertical line with the ratchet 17^b, 60 so that the ratchet pawl 20 can properly en-

gage said ratchet. 19^b is the retarding lever spring mounted on the pivot pin 12^a, on which the trigger is pivoted. One end of the spring rests on the top of the trigger-guard and the other end bears against the pin 19^c which projects laterally from the left hand side of the retarding lever, forwardly of pivot pin 19^a. Pin 19^c is undercut to hold said spring and pin in engagement. This spring therefore exerts its pressure to rotate the forward end of the retarding lever upwardly, from the position shown in Fig. 1 to that shown in Fig. 3.

Projecting laterally from the right hand side of the rear end of the retarding lever 80 and integral therewith is lever-piece 19^d with longitudinally extending front and rear arms (Figs. 2 and 5).

Between the upwardly projecting arm 12^c of the trigger and the right hand side of the trigger-guard, and just forward of the lever piece 19^d, is the retarding lever latch 21, pivoted on a fixed pin 21^a, which projects inwardly from right hand side of the trigger-guard. Seated in said latch is the latch 90 spring 21^b bearing at its lower end against the trigger-guard, as shown in Fig. 5. In the rear face of said latch is a recess 21^c. As will be seen by reference to Fig. 5, the latch spring normally holds said latch in 95 its rearward position with the shoulder of said recess 21^c engaging the top face of the shelf 19^e on the end of the front arm of the lever piece 19^d when the retarding lever is in its lowered position (Fig. 1), thereby 100 holding the retarding lever in its lowered or operative position, as shown in Fig. 1. The shelf 19^e on the end of the front arm of the lever piece 19^d projects laterally and to the right, beyond the inner edge of the longitudinal right hand ledge 13^b on the top right hand side of the trigger-guard, as shown in Fig. 2. The upward movement of retarding lever 19 is limited by the rear end of lever piece 19^d engaging the top face of the trigger-guard, as shown in Fig. 3. The downward movement of retarding lever 19 is limited by engagement of the shelf 19^e with the top of the said longitudinal ledge 13^b.

110 The top of the trigger adjacent the arm 12^c forms a shoulder 12^d (Fig. 7) which, unless the retarding lever is in its uppermost or inoperative position, will engage the bottom face of said lever before the top of the arm 12^c will engage the front arm of the sear.

115 The pivot pins 14^a, 19^a, 12^a and 17 are held in their seats when the rifle is assembled by the sides of the breech casing.

120 The operation of the retarding device can now be readily understood. In Fig. 1 the parts are in the position which they assume when a shot is being fired. Upon the firing of a shot the action-slide immediately re-

coils and just as it moves forward after the limit of recoil, the rear end of the sear engages the cocking shoulder 2^a, holding the action-slide and hammer cocked. The action-slide, by its cocking shoulder, strikes the rear end of the sear a sharp blow as the action-slide shoots forward under the pressure of its reaction spring 5. The force of this blow will be buffered and the danger of injuring the parts thereby avoided by the longitudinal movement of the sear, permitted by its pivot slot 14^b, against the rearward pressure of the sear spring. Moreover, the front end of the sear in moving forward from the position of Fig. 1 to that of Fig. 3, will strike the rear face of latch 21, rotate it on its pivot against the pressure of its spring and disengage the shoulder of recess 21^c from engagement with the shelf 19^e on the forward arm of the lever piece 19^d. Retarding lever 19 is now free to swing upwardly under the influence of its spring 19^b. On the upward swing of the retarding lever the teeth on the ratchet pawl 20 engage the ratchet 17^b, rotating the ratchet and the escapement wheel 17^c, the teeth of which engage with the escapement pawl 18, which operates in a well-known manner to retard the rotation of the escapement wheel, thereby by retarding the upward movement of the retarding lever. Until the retarding lever has reached its uppermost position, pull on the trigger can not bring arm 12^c on the trigger into engagement with the sear to rotate the sear and release the action-slide because of the position of the retarding lever overlying the shoulder 12^d on the trigger. When the retarding lever has reached its uppermost position, however, as in Fig. 3, upon pulling the trigger the projection 12^e will engage the front end of the sear before the shoulder 12^d will strike the bottom of the retarding lever and the action-slide and hammer will be released to move forward to fire the next cartridge.

On the forward motion of the action-slide the bottom of the slide engages the top of the retarding lever, forcing it down to its lowered position (Fig. 1) against the pressure of its spring. The retarding lever will swing downward so rapidly that the teeth on pawl 20 will ride over the teeth on ratchet 17^b and there will be no appreciable retarding of the forward movement of the action-slide. If the trigger is being held back for full automatic action the retarding lever, on its downward swing, will engage the shoulder 12^d on the trigger and force the trigger downwardly against the pull of the operator and thereby insure that the sear will return to and remain in cocking position until the retarding lever has again returned to its uppermost and inoperative position. By continuing to pull back on the trigger the rate of firing can be made as rapid as the opera-

tion of the retarding mechanism permits. When the action slide moves forward, the sear, actuated by its spring, is returned to its rearward position with its rear end raised for again engaging the cocking shoulder of the action-slide on the next recoil thereof. Rotation of the sear on its pivot pin under the influence of its spring is limited by the stud 22, which projects upwardly from the top face of the trigger-guard and which is engaged by the bottom face of the front arm of the sear when the sear is in its normal position, as shown in Fig. 7.

When the retarding lever is lowered, the front face of the shelf 19^e rides over the rearwardly inclined face of the catch 21, rotating said catch forwardly against its spring, until the retarding lever reaches the limit of its downward movement, when said shelf registers with the recess 21^c of the latch and the latch snaps back with its shoulder engaging the end of the shelf, holding the retarding lever in its downward position as shown in Figs. 1, 2 and 5, until the latch is again engaged and pushed out of locking position by the longitudinal movement of the sear, as hereinbefore described.

The minimum length of time elapsing, therefore, between shots (without counting the very brief time consumed in the recoil and return of the firing mechanism) will be the length of time taken by the retarding lever in rising from its lowered or operative position to its raised or inoperative position, and this will be governed by the weight of the escapement pawl and by the number of teeth in the ratchet pawl and escapement wheel.

The retarding lever and its spring can be removed from the trigger-guard without affecting the operation of the gun except that there will then be nothing to retard the rate of firing. By holding back the trigger the sear will be kept from any cocking engagement with the action-slide, permitting full automatic action.

It will be noticed that when my retarding mechanism is operating, a continued pull on the trigger is essential for full automatic action, as is the case when the retarding mechanism is dispensed with.

What I claim and desire to secure by Letters Patent is:—

1. In an automatic fire-arm the combination of recoiling firing mechanism, a sear, a trigger, and firing retarding mechanism comprising trigger locking means rendered operative on the forward firing movement of the firing mechanism to lock the trigger from sear actuating movement, means to move said locking means to inoperative position, means which render said moving means operative on the motion of the firing mechanism following discharge and means for retarding the movement of said locking

means from operative to inoperative position, whereby the minimum time elapsing between shots may be increased.

2. In an automatic fire-arm the combination of recoiling firing mechanism, a sear, a trigger, and firing retarding mechanism comprising trigger locking means rendered operative on the forward firing movement of the firing mechanism to lock the trigger from 5 sear actuating movement, means for automatically locking said trigger locking means in said operative position and which is released by the cocking of said firing mechanism following discharge, means for moving 10 said trigger locking means to inoperative position upon the release of said locking means, and means for retarding the movement of said trigger locking means from operative to inoperative position.

20 3. In an automatic fire-arm, the combination of recoiling firing mechanism, a sear, a trigger, and firing retarding mechanism comprising trigger-locking means rendered operative to lock the trigger from sear-actuating movement on the forward firing movement of the firing mechanism and means rendered operative by the cocking of said firing mechanism following recoil to move the trigger-locking means to inoperative position, whereby after each shot the trigger 25 will be locked from sear-actuating movement until after the firing mechanism has been cocked by the sear.

4. In an automatic fire-arm, the combination of recoiling firing mechanism, a sear, a trigger, and firing retarding mechanism comprising a trigger-locking element rendered operative on the forward firing movement of the firing mechanism to lock the 30 trigger from sear-actuating movement, means rendered operative by the cocking movement of said firing mechanism to move said trigger-locking element from operative to inoperative position, and means for retarding the said movement of said trigger-locking element, whereby on the firing of each shot said trigger will be locked from sear actuating movement until said element 35 has moved from operative to inoperative position and whereby the time taken for such movement will be increased.

5. In an automatic fire-arm, the combination of recoiling firing mechanism, a sear, a trigger and firing retarding mechanism comprising a spring-pressed trigger-locking element moved to operative position against the pressure of said spring on the forward firing movement of the firing mechanism to lock the trigger from sear-actuating movement, means for locking said element in its said 40 operative position rendered inoperative on the cocking movement of said firing means, and means for retarding the rate of movement of said element from operative to inoperative position, whereby on the firing of 45

each shot said trigger will be locked from sear-actuating movement until after the firing mechanism has been cocked by the sear and whereby there will be a lapse of time 50 between shots at least equal to the time taken for said trigger-locking element to move from operative to inoperative position.

6. In an automatic fire-arm, the combination of recoiling firing mechanism, a trigger, a sear mounted for limited longitudinal movement, a spring-pressed trigger-locking lever actuated by the firing mechanism on its forward firing movement to operative position against the pressure of its spring, a lever catch to engage said lever and hold it 55 in trigger-locking position and which is positioned to be disengaged from said lever by the forward movement of said sear, whereby when the firing mechanism engages the sear on its cocking engagement therewith said sear will engage said catch to release said lever for movement to inoperative position under the influence of its spring.

7. In an automatic fire-arm, the combination of recoiling firing mechanism, a sear, a trigger, and fire-retarding mechanism comprising a movable trigger-locking element, a spring therefor, means for retarding the movement of said trigger-locking element 60 from operative to inoperative position, means for locking said element in its operative position, said element being moved to operative position against the pressure of its spring by said firing mechanism on its forward firing movement and being held in 65 said position by said locking means, and means actuated by said firing mechanism on its cocking movement to disengage said locking means.

8. In an automatic fire-arm, the combination of recoiling firing mechanism, a trigger, a sear having limited longitudinal movement, yielding means for normally holding said sear in its rearward position, a trigger-locking lever actuated by the firing mechanism on its forward firing movement to lock the trigger from sear-actuating movement, lever-locking means which locks said lever 70 in its operative position, said locking means being positioned to be engaged by the sear when said sear is in its forward position, whereby when the sear and firing mechanism come into cocking engagement the sear will be moved forwardly and will engage said locking means, thereby unlocking said lever.

9. In an automatic fire-arm, the combination of recoiling firing mechanism, a trigger, a sear, a trigger-locking lever, means for moving said lever to operative position on the firing of a shot, means for moving said lever from operative to inoperative position, escapement means engaged by said lever which retards said movement of said lever 75 from operative to inoperative position, a 80

latch for locking said lever in its operative position, and means actuated by the firing mechanism on its cocking movement for disengaging said latch from locking engagement with said lever, as and for the purpose described.

10. In an automatic fire-arm, the combination of recoiling firing mechanism, a trigger, a sear having limited longitudinal movement, a trigger-locking lever, means for moving said lever away from operative position, means for retarding said movement of said lever, and a latch which locks said lever in its operative position and which is actuated to unlock said lever by the forward movement of the sear following cocking engagement with the firing mechanism.

11. In an automatic fire-arm, the combination of recoiling firing mechanism, a trigger, a sear having limited longitudinal movement, yielding means to normally hold said sear in its rearward position, a trigger-locking lever actuated by the firing mechanism on its forward firing movement to operative position to lock the trigger from sear-actuating movement, means for moving said lever from operative to inoperative position, a yieldingly mounted latch which locks said lever from movement when in its operative position and which is positioned to be engaged by the sear when said sear is in its forward position, whereby the firing mechanism will be cocked by the sear after each recoil and whereby the forward motion of the sear following the cocking engagement of sear and firing mechanism will both buffer the blow of said engagement and will disengage said latch from said lever, permitting said lever to move to inoperative position to unlock the trigger.

12. In an automatic fire-arm, the combination of recoiling firing mechanism, and firing retarding mechanism comprising a locking lever, means rendered operative by the firing mechanism on its initial forward movement following recoil to move said lever from locking to unlocking position, means for retarding said movement of said lever, and means for moving said lever to locking position on the further forward movement of said firing mechanism.

13. In an automatic fire-arm, combination of recoiling firing mechanism, a sear, a trigger, a locking lever which is moved by the firing mechanism on its forward firing movement to operative position overlying the trigger, a latch to engage and lock said lever in said position, a lever spring, means actuated by the firing mechanism on its initial forward movement following recoil to disengage said latch from said lever, escapement means engaged by said lever to retard the movement of said lever from operative to inoperative position.

14. In an automatic fire-arm, combination of recoiling firing mechanism, a sear having limited longitudinal movement, a trigger, and firing retarding mechanism comprising a locking lever, a lever spring, a lever locking latch and escapement mechanism engaged by said lever, as and for the purpose described.

15. In an automatic fire-arm, combination of recoiling firing mechanism and firing retarding mechanism comprising a lever rendered operative on the forward firing movement of the firing mechanism to prevent actuation of the firing mechanism to fire a shot, means to move said lever from operative to inoperative position, and means for retarding said movement of said lever comprising a toothed pawl carried by said lever, a ratchet wheel, an escapement wheel and pawl actuated by said ratchet, and a spring holding said toothed pawl in yielding engagement with said ratchet, the teeth on said pawl and ratchet being so organized that when in the operation of the fire-arm said lever moves from operative to inoperative position said pawl will rotate said ratchet, and when said lever is moved from inoperative to operative position the teeth on said pawl will slide over the teeth on said ratchet without any appreciable rotation of the same.

This specification signed and witnessed this 19th day of Sept., A. D. 1923.

JOHN M. BROWNING.

In the presence of:

C. J. EHBETS,
ARTHUR L. ULRICH.
